EPERGNE

Filed May 29, 1948

Margaret M. Lewis
INVENTOR

UNITED STATES PATENT OFFICE

156,017

DESIGN FOR AN EPERGNE

Margaret M. Lewis, New York, N. Y.

Application May 29, 1948, Serial No. 146,692

Term of patent 7 years

(Cl. D36—2)

To all whom it may concern:

Be it known that I, Margaret M. Lewis, a citizen of the United States, residing at No. 295 Central Park West, in the city of New York, county and State of New York, have invented a new, original, and ornamental Design for Epergnes, of which the following is a specification, reference being had to the accompanying drawing, forming part thereof.

The figure is a perspective view of an epergne, showing my new design.

I claim:

The ornamental design for an epergne, as shown.

MARGARET M. LEWIS.
